P. H. MACK,
OIL WELL PACKER,
APPLICATION FILED NOV. 28, 1919.

1,395,719.

Patented Nov. 1, 1921.

UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

OIL-WELL PACKER.

1,395,719.

Specification of Letters Patent.

Patented Nov. 1, 1921.

Application filed November 28, 1919. Serial No. 341,173.

To all whom it may concern:

Be it known that I, PATRICK H. MACK, a citizen of the United States, residing at Bradford, in the county of McKean and 5 State of Pennsylvania, have invented certain new and useful Improvements in Oil-Well Packers, of which the following is a specification.

The prime object of my invention is to 10 provide a new and improved well packer structure including means adapted to contain a suitable material, such as cement, for filling in the bottom of the hole or well.

In the drawings I have shown a packer 15 of the type shown, described and claimed in a companion application Serial No. 341,172, filed November 28, 1919, but it will be evident that the well packer structure of the 20 present invention is not limited to a combination including the particular type of packer shown.

In the accompanying drawings which illustrate an application of my invention,

Figure 1 is a central longitudinal sectional view of a packer structure embodying my invention;

Fig. 2, a sectional view taken on line II—II of Fig. 1;

Fig. 3, an enlarged detail sectional view 30 showing lower portion of container with valve seated;

Fig. 4, a similar view showing valve unseated; and

Fig. 5, a horizontal section taken on line 35 V—V of Fig. 3.

Referring to the drawings and as preferred, the packer structure includes a body member 1, this member being preferably solid and of cylindrical form. The upper 40 end of the body is provided with an externally threaded extension 2 and its lower end is reduced as shown at 3, and is also provided with a cone-shaped extension 4. Extension 4 may be formed integral with 45 the body or it may be a separable member; in either case it is provided with an opening 5 adapted to receive a pin 6 whereby the lower telescoping end member or sleeve 7 is secured to the body. Pin 6 is designed 50 to be broken during the operation of setting the packer, thereby permitting the lower end of the body or the extension to be lowered within member 7.

The telescopingly connected member 7, 55 which is of hollow construction, has its inte-

rior wall provided with teeth or serrations 8 and is also formed with a reduced externally threaded portion 9. 10 designates the upper end member or cap which is formed with a threaded recess 11 designed to 60 receive the upper threaded extension 2 of the body member, and with a horizontally extending opening 12, the latter being designed to contain a pin 12', whereby the packer structure, by the employment of a wire or 65 other means, may be connected with a string of tools, not shown. Cap 10 is also formed with an annular inclined shoulder 13.

Surrounding the reduced portion 3 of body member 1 is a spring or a plurality 70 of springs 14, the upper end of spring 14 bearing against a shoulder of member 1 and the lower end, or ends in case a plurality of springs are employed, against toothed elements or members 15. Toothed members 75 15 are positioned between the extension 4 and the toothed wall 8 of member 7 and are maintained in the desired positions by the spring 14 and dowel pin 16. It will be understood that as the members 15 are moved 80 downwardly in the bore of sleeve 7, the teeth of said members will engage the teeth 8 of member 7; thereby locking member 7 to the body at any desired elevation.

The compressible packing element or elements surrounding the body, as illustrated and as preferred, include two sets of compressible elements 17 and 18. The elements 17, located at the upper and lower ends of the packing, are designed upon compression 90 to be forced inwardly against the body for the purpose of forming seals at the upper and lower ends of the packing to prevent fluids working in between the body and the packing, while the elements 18 are designed 95 to be forced outwardly against the wall of the well, as is usual.

Elements 18 have top and bottom faces inclined from the outer periphery inwardly, while the elements 17 have their top and 100 bottom faces inclined in an opposite direction from the faces of elements 18. Interposed between the elements 18 are rigid ring members 19 having their faces inclined in opposition with the corresponding faces of the compressible elements 18. The upper packing element 17 is held between the shoulder 13 of cap or upper member 10 and a rigid member 20, and the lower element 17 between a similar rigid member 21 and an in- 110

clined face 22 of an annular wedge shaped abutment or member 23. The compressible elements may be formed of any suitable material; I have found lead to be a desirable material for some purposes.

Surrounding the body and interposed between the member 23 and a wedge member 24 are slips 25, 26 designates means for retaining the slips in position prior to their being forced out into contact with the wall of the well.

The container member of the packer structure is designed to be connected with the lower threaded portion 9 of the sleeve 7 and 15 as illustrated, the container includes a hollow cylindrical body 27 having its lower end provided with a valve controlled closure 28 and a plunger member 29. 30 designates a coupling member into which the upper end 20 of member 29 is entered, said coupling being adapted to engage portion 9 of sleeve 7.

Closure 28 is formed with a plurality of passageways 31 through which the material carried in the container is discharged. 32 25 designates a valve device for controlling the discharge of material from the container and said valve device includes a depending stem 33 and a lower end member 34.

The packer structure illustrated is designed to be lowered into position in a well and set by a string of tools to which the structure is detachably connected. It will be understood that when the lower member 34 of the valve device strikes the bottom of 35 the well, the valve will be raised from its seat, thus opening the passageways for the discharge of the cement or other material, and that the plunger member 29 as it is lowered by the packer proper will force the 40 material out through said passageways. When the downward movement of the plunger has been checked, it will cause the opposing end members of the packer to be moved together, expanding the packing into 45 contact with the wall of the well, confining the cement, and permitting it to set. Thus, the operation of the valve, the movement of the plunger, and the actuation of the packing expanding means will follow in rapid 50 sequence.

What I claim is:

1. The combination with a well packer, of a container adapted to be secured to the lower end of the packer and including a 55 hollow body, a closure for the lower end of the body, said closure provided with an outlet passage, means controlling the passage of material through said outlet passage, and means whereby the packer will 60 be expanded after the controlling means has been moved to open the outlet passage.
2. The combination with a well-packer, of a container adapted to be secured to the

lower end of the packer and including a hollow body, a plunger operable within the body and serving to connect it with the packer, a closure for the lower end of the body, said closure provided with an outlet passage, and means controlling the passage of material through said outlet passage.

3. The combination with a well packer having opposing end members, a body member, packing elements surrounding the body and disposed between the end members, of a container carried by the packer, and means 75 for connecting the container to one of the end members.

4. The combination with a well packer having opposing end members, a body member, packing elements surrounding the body and disposed between the end members, of a container carried by the packer, and means 80 for connecting the container to one of the end members, said means including a plunger in the container operated by the packer. 85

5. The combination with an oil well packer having expandible packing means thereon, of a container carried by the packer, and a plunger in said container connected with the packer and adapted to 90 be actuated thereby.

6. The combination with an oil well packer having expandible packing means thereon and means for expanding the packing means, of a container carried thereby, 95 and means for connecting the packer and container for expressing the material from the container and causing said packing expanding means to actuate.

7. The combination with an oil well packer having expandible packing means thereon and means for expanding the packing, of a container carried by the packer having outlet 100 passages therein, valve means for controlling the passages, a plunger for forcing material from the container, said plunger being connected with said means for expanding the packing, said valve means, plunger and packing expanding means being arranged to operate in sequence.

8. The combination with a well packer having expandible packing means thereon and means for expanding the packing, of a container carried by the packer, plunger 115 actuated means for causing the contents of the container to escape, said plunger actuated means and packing expanding means being connected and arranged to operate in sequence.

In testimony whereof I affix my signature in presence of two witnesses.

PATRICK H. MACK.
